UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

CALL-DISTRIBUTING SYSTEM.

1,215,911.

Specification of Letters Patent. Patented Feb. 13, 1917.

Application filed January 11, 1915. Serial No. 1,549.

To all whom it may concern:

Be it known that I, HENRY P. CLAUSEN, a citizen of the United States, residing at Mount Vernon, in the county of Westchester and State of New York, have invented certain new and useful Improvements in Call-Distributing Systems, of which the following is a full, clear, concise, and exact description.

10 This invention relates to a call distributing system, and is particularly designed for a system in which certain subscribers' lines which may be termed "heavy users" are so arranged that calls from such lines 15 are automatically extended to an operator's position where no unanswered calls are present at the time. When a subscriber is connected to a trunk at one of the operators' positions through a call distributing switch, 20 his line number is lost.

When party lines are operated on this system, it is desirable to provide a reverting busy test, which shall operate through the call distributing switch. Unless such a test 25 is provided, one subscriber calling for another subscriber on the same line will not receive satisfactory services, as the operator often will not be aware that the calling and called parties are both on the same line. 30 Therefore, when the operator tests a multiple of the calling subscriber's line, she will report the line busy, and unless the calling subscriber knows that the party called is on his own line, the call will be unsuccessful.

35 One of the objects of this invention therefore, is the provision of circuits which will provide a reverting busy test in a system employing call distributing switches.

Another object of the invention resides in 40 the circuits being so arranged that a calling subscriber may cause a connection through his distributing switch to be broken down at any time prior to its being taken up by the operator, but in which the subscriber cannot break down the connection 45 after the operator has placed an answering plug in the trunk jack.

The advantages of this arrangement will 50 be apparent when it is understood that a large proportion of the calls which originate upon lines provided with called distributing apparatus are false calls. It is, therefore, not desirable to lock up a circuit 55 when a telephone line is accidentally short-

circuted for then it becomes necessary for 55 an operator to insert the answering plug in the spring jack before the connection may be broken down or the operator's position rendered idle and available to other incoming calls.

60 The drawing discloses a system embodying the advantages above recited.

Referring to the drawing—1 represents a subscriber's line which in the present case may be a party line.

65 The distributing switch herein shown is of a character similar to that disclosed in my Patent No. 1,131,911, patented March 16, 1915. The brushes which are advanced step by step, electrically unite the contacts on 70 which they rest with the adjacent conducting segments. It is thought the operation of this switch will be readily understood from the following description of the invention.

75 When a subscriber on line 1 removes his receiver from its hook, a circuit is completed from grounded battery 2 through the left winding of line relay 3, left armature of cutoff relay 4, left side of the line, the subscriber apparatus of the calling subscriber 80 the right side of the line, the right armature of relay 4, right winding of line relay 3 to ground. Relay 3 attracts its armature, completing an energizing circuit through relays 5 and 6. The operation of relay 6 causes 85 the signal lamp 7 to glow.

Assuming that the distributing trunk or outlet, upon which the switch brushes now rest is busy, a circuit will be completed as will appear later from grounded battery 8 90 through the left armature and front contact of trunk cutoff relay 9 at the switch associated with said busy trunk and impedance coil 10 to the multiple test contacts of the trunk, brush 11 and conducting arc 12 of the 95 seeking switch, lower normal contact of relay 13, upper contact of relay 5, stepping magnet 14, and interrupter 15 to ground. Stepping magnet 14 will be energized, attracting its armature, causing the pawl 16 100 to ride up over one tooth of the ratchet wheel 17 which carries the switch brushes. When interrupter 15 breaks this circuit the armature and pawl 16 will be retracted by spring 18, causing the switch brushes to engage the 105 contacts of the next trunk or outlet. Had the switch brushes rested on the contacts of an idle trunk entering an operator's posi-

tion at which an unanswered call existed, the result would have been the same, as busy potential would then be supplied through an armature of relay 30, as will presently appear. This stepping operation will be repeated until the test brush 11 engages a contact of an idle trunk terminating at an idle operator's position upon which no battery potential will be present. During the stepping operation a circuit existed from battery 19 through the lower contact of relay 5, upper winding of holding relay 13, normal lower contact of relay 13, upper contact of relay 5, stepping magnet 14 and interruper to ground. Relay 13 was not operated over this circuit, however, during the stepping operation, due to the short circuit of its winding which extended from battery through impedance 10 and the test brush. Upon engaging an idle line, this short circuit is removed and relay 13 attracts its armature. Relay 13 by the attraction of its lower armature interrupts its energizing circuit, but will not fall off as it is slow to release and also because a momentary holding circuit now extends from grounded battery 19 through lower armature of relay 5, upper winding of relay 13, lower front contact of relay 13, lower winding of relay 13 and cut off relay 4 to ground. Relay 13 at its upper contacts now extends the calling subscriber's line to the switch brushes.

When the switch brushes stop on the contacts of an idle trunk, a circuit is completed from battery 21, left winding of trunk line relay 22, middle armature of cut off relay 9, switch brush 23, conductor 24, innermost upper armature of relay 13, left side of the subscriber's line, the calling subscriber's substation apparatus, right side of the calling line, upper armature of relay 13, brush 25, distributing trunk or outlet conductor 26, innermost armature of relay 9, right winding of relay 22 to ground.

Relay 22 at its left armature causes battery potential to be supplied to the test contact of the now busy trunk through impedance coil 10, and also completes a locking circuit for holding relay 13 extending from the test contact, through lower armature and front contact of relay 13, lower winding of said relay and cut off relay 4 to ground.

Relay 4 now operates, not having previously operated, due to the inclusion in its circuit of the resistance of both windings of relay 13. The energization of relay 4 interrupts the circuit of line relay 3 which in falling off causes the deenergization of relays 5 and 6.

Relay 22 at its right armature completes a circuit from battery through relay 27 and answering lamp 28' in series. This causes the lamp to glow and the energization of relay 27.

Relay 27 in turn completes a circuit for

relay 28 which upon energization completes a circuit for the pilot lamp 29 and also for relay 30.

Relay 30 in energizing supplies busy potential through its several armatures to the test contacts of all the trunks entering the operator's position, including the trunk just seized. The supplying of test potential to this trunk, however, is without function at this time, as test potential is already supplied from battery 21 through the left armature of relay 22.

If the circuit on the calling line is now momentarily opened, relay 22 will become deenergized, causing the deenergization in sequence of relays 27, 28 and 30. As the armatures of relays 22 and 30 would now be retracted, battery would be removed from the test contact of the trunk and relays 13 and 4 would become deenergized, and all the apparatus with the exception of the switch which has no normal position, would be returned to normal.

We will now assume that the operator inserted the answering plug 31 in the outlet jack 32 prior to the opening of the subscriber's line. Supervisory relay 32' will become energized from battery 33 through ring contacts of the plug and jack, brush 23, conductor 24, innermost upper contact of relay 13, left side of subscriber's line, substation apparatus, right side of subscriber's line, outermost upper contact of relay 13, brush 25, conductor 26, tip contacts of the jack and plug back to battery. Relay 32' will be energized, completing a circuit from battery 34 through contact of the supervisory relay, sleeve contacts of plug and jack and cutoff relay 9 to ground.

Relay 9 is operated and supplies test potential to the test contact of the trunk through its left armature, thus completing another path to battery for the holding circuit for relays 13 and 4. Relay 9 at its middle and right armatures opens the circuit of relay 22 which is deenergized, causin in the deenergization in sequence of relays 27, 28 and 30. Relay 9 will remain energized as long as the plug remains in the jack and therefore the opening of the subscriber circuit will now not cause the release of the distributing apparatus, but will merely cause the deenergization of relay 32' and the display of the supervisory signal 35.

The operator now closes her listening key 36 and obtains from the calling subscriber the number of the subscriber wanted.

Assuming that the calling and wanted subscribers are both on the same line, the operator not knowing this fact will touch the tip of the calling plug 37 to the sleeve of the jack 38 of the calling line. The calling line being busy, a line circuit will now extend from grounded battery 8 through the front contact of left armature of relay 9, 130

impedance coil 10, brush 11, lower front contact of relay 13, lower winding of relay 13, sleeve of jack 3, tip of plug 37, listening key contact 39 and relay 40 to ground. Relay 40 will be energized, completing a circuit from ground through the secondary winding 41 of the busy tone apparatus 42, armature and contact of relay 43, armature and contact of relay 40, listening key contact 44, sleeve contacts of plug 31 and jack 32, condenser 45, trunk test contact, brush 11, conducting segment 12, lower innermost contact of relay 13, lower winding of relay 13, sleeve of jack 38, tip of plug 37, listening key contact 39, conductor 46, through the operator's set to conductor 47, listening key contact 44, supervisory relay 48, to ground through battery 33. The impedance coil 10 is provided to prevent the short circuiting of the operator's set in the busy tone circuit through battery 8.

The operator now hearing the distinctive tone produced by the apparatus 42 will be informed that the called and calling parties are both on the same line, and will thereupon remove the plugs 31 and 37 from jacks 32 and 38 and signal the called subscriber in the usual manner.

If, for any reason, it is desired to make an operator's position temporarily busy, the key 49 is operated, energizing relay 80 placing busy potential permanently upon the test contacts of all the trunks entering the operator's position. Although a plurality of batteries are represented on the drawing, these may be and in practice probably would be one and the same source of current.

It is obvious that other systems embodying the salient features of this invention, but differing widely in detail from that herein shown may be readily designed. Applicant therefore desires it understood that his invention is to be limited merely by the scope of the appended claims.

45 What is claimed is:

1. In a telephone system, a subscriber's line, trunks, a switch for automatically uniting said line to an idle trunk upon the initiation of a call on said line, connection switches for extending said trunks, a pair of relays to control the release of said first mentioned switch, one of said relays being under the control of the calling subscriber's hook switch and the other said relay being under the control of contacts of said connection switch, and means whereby the operation of the last mentioned relay removes the control from the other said relay.

30 2. In a telephone system, a subscriber's line, a switch, contacts at said switch forming the terminals of said line, said terminals being normally disconnected from said line, trunks terminating at said switch and extending to a plurality of operators' positions, means actuated by the initiation of a

call on said line for operating said switch to connect said line to an idle trunk extending to an idle operator's position, a connection switch at said position for extending said trunk, and means operated upon the connection to said idle trunk for connecting said line to said contacts, said last mentioned means being under the joint control of the calling subscriber's hook switch and said connection switch. 75

3. In a telephone system a line, trunks, a switch for automatically joining said line to said trunks upon the establishment of a call upon said line, a connection switch for extending said trunk, a relay having a circuit controlled by said connection switch, a relay for maintaining said line in association with said trunk and a locking circuit for said second relay extending through a front contact thereof and a contact of said first-mentioned relay. 80

4. In a telephone system, a line, trunks, a switch for automatically joining said line to an idle trunk upon the establishment of a call on said line, a connection switch for extending said trunk, a relay having a circuit controlled by said connection switch, a relay having a circuit controlled through contacts of said automatic switch, a relay for maintaining said line in association with said trunk, and a locking circuit for said last-mentioned relay extending through a front contact thereof and completed through either a contact of said first-mentioned relay or a contact of said second-mentioned relay. 95

5. In a telephone system, an exchange, a plurality of operators' positions at said exchange, subscribers' lines, switches, distributing trunks extending from said switches to said operators' positions, means for causing one of said switches to automatically connect a calling line to an idle trunk extending to an idle operator's position, a connecting circuit to said position, a connection switch for uniting said circuit to said trunk, 100 means associated with the other end of said connecting circuit for testing a wanted subscriber's line, a tone device and means for associating said tone device with an operator's set when the calling line is tested. 110

6. In a telephone system, telephone lines, automatic distributing switches, said lines terminating at said switches and in jacks, trunks extending from said switches, means for causing a switch to automatically unite a calling line with an idle trunk, a cord circuit, a connection switch for uniting said circuit to said trunk, a plug associated with the other end of said cord circuit and means for signaling the operator when the tip of 120 said plug is united with the sleeve contact of the calling line jack.

7. In a telephone system, a subscriber's line, automatic distributing switches, said lines terminating at said switches and in 130

- jacks, distributing trunks extending from said switches, means for causing one of said switches to automatically connect a calling line to an idle trunk, a connecting circuit, 5 a switch for uniting said circuit with said trunk, a plug associated with the other end of said connecting circuit, a tone device and means for transmitting a tone from said device to the operator's set when the tip of 10 said plug is united with the sleeve contact of the calling line jack.
8. In a telephone system, telephone lines, automatic distributing switches, said lines terminating at said switches and in jacks, 15 trunks extending from said switches, means for causing a switch to automatically unite the calling line to an idle trunk, a cord circuit, a plug and jack for connecting said cord circuit to said trunk, a plug at the other 20 end of said cord circuit, a tone device and means for associating said tone device with an operator's set when the tip of the last mentioned plug is joined to the sleeve contact of the calling line jack.
- 25 9. In a telephone system, an exchange, a plurality of operators' positions at said exchange, switches, subscribers' lines terminating at said switches and in jacks, distributing trunks extending from said switches to 30 said operators' positions, means for causing a switch to automatically unite a calling line with an idle trunk extending to an idle operator's position, a cord circuit at said position, a switch for uniting said circuit 35 with said trunk, a plug associated with the other end of said circuit, a signal device and means for causing the effective operation of said signal device upon uniting the tip of said last mentioned plug with the 40 sleeve contact of the calling line jack.
10. In a call distributing system, telephone lines, an automatic distributing switch at which said lines terminate, distributing trunks terminating at one end in 45 said switches and at the other end in connection switches, means for causing the distributing switch to unite a calling line with an idle distributing trunk and means for
- electrically connecting the test contacts of said trunks at said switches with the sleeve 50 contacts of said connection switches.
11. In a call distributing system, telephone lines, automatic distributing switches at which said lines terminate, distributing trunks terminating at one end in said distributing switches and at the other end in connection switches, means for causing a distributing switch to unite a calling line with an idle distributing trunk, and means when so united for electrically connecting 55 the sleeve contact of said connection switch with the test contact of said line.
12. In a call distributing system, telephone lines, automatic distributing switches, said lines terminating at said switches and 60 in jacks, distributing trunks terminating at one end in said switches and at the other end in jacks, means for causing a distributing switch to unite a calling line with an idle distributing trunk and means when so 65 united for electrically connecting the sleeve of the distributing trunk jack with the sleeve of the calling line jack.
13. In a telephone exchange system, telephone lines, automatic distributing switches 70 at which said lines terminate, distributing trunks terminating at one end in said switches, means for causing a distributing switch to select an idle distributing trunk and unite a calling line therewith, a plug 75 and jack switch for extending said trunk, a relay, a circuit therefor extending through the sleeve contacts of said plug and jack, a line cut-off relay, a holding relay for maintaining said line united with said trunk, 80 and a locking circuit for said holding relay extending through said cut-off relay, front contact of said holding relay, and a contact of said first mentioned relay.
- In witness whereof, I hereunto subscribe 85 my name this 8th day of January, A. D. 1915.
